United States Patent Office

Des. 179,346
Patented Dec. 4, 1956

179,346

KNOB ROSE

Glen Holland, Villanova, Pa.

Application March 23, 1956, Serial No. 40,759

Term of patent 3½ years

(Cl. D50—6)

Fig. 1.

Fig. 2.

Fig. 3.

Fig. 1 is a front elevation of a knob rose embodying my new design. Fig. 2 is a side view of the knob rose. Fig. 3 is a cross section on the line 3—3 in Fig. 1.

I claim:

The ornamental design for a knob rose, substantially as shown.
